(57) **CLAIM**

The ornamental design for a multi-chamber processing apparatus, as shown and described.

DESCRIPTION

FIG. 1 is a front view of a first embodiment of a multi-chamber processing apparatus embodying our design;

FIG. 2 is a back view thereof;
FIG. 3 is a left-side view thereof;
FIG. 4 is a right-side view thereof;
FIG. 5 is a plan view thereof;
FIG. 6 is a bottom view thereof;
FIG. 7 is a front view of a second embodiment of a multi-chamber processing apparatus embodying our design;
FIG. 8 is a back view thereof;
FIG. 9 is a left-side view thereof;
FIG. 10 is a right-side view thereof;
FIG. 11 is a plan view thereof;
FIG. 12 is a bottom view thereof;
FIG. 13 is a front view of a third embodiment of a multi-chamber processing apparatus embodying our design;
FIG. 14 is back view thereof;
FIG. 15 is a left-side view thereof;
FIG. 16 is a right-side view thereof;
FIG. 17 is a plan view thereof;
FIG. 18 is a bottom view thereof;
FIG. 19 is a front view of a fourth embodiment of a multi-chamber processing apparatus embodying our design;
FIG. 20 is back view thereof;
FIG. 21 is a left-side view thereof;
FIG. 22 is a right-side view thereof;
FIG. 23 is a plan view thereof;
FIG. 24 is a bottom view thereof;
FIG. 25 is a front view of a fifth embodiment of a multi-chamber processing apparatus embodying our design;
FIG. 26 is a back view thereof;
FIG. 27 is a left-side view thereof;
FIG. 28 is a right-side view thereof;
FIG. 29 is a plan view thereof; and,
FIG. 30 is a bottom view thereof.
